UNITED STATES PATENT OFFICE.

HOMER E. LEASH AND JOHN L. SCHWENK, OF NEW WESTMINSTER, BRITISH COLUMBIA,
CANADA; SAID LEASH ASSIGNOR TO SAID SCHWENK.

MEANS FOR PRINTING AN ENLARGEMENT FROM A NEGATIVE-FILM.

1,138,963.

Specification of Letters Patent. Patented May 11, 1915.

Application filed February 21, 1914. Serial No. 820,121.

To all whom it may concern:

Be it known that we, HOMER E. LEASH and JOHN L. SCHWENK, citizens of the Dominion of Canada and of the United States of America, respectively, residing at New Westminster, in the Province of British Columbia, Canada, have invented certain new and useful Improvements in Means for Printing an Enlargement from a Negative-Film, of which the following is a specification.

This invention relates to a device for photographically printing an enlargement from a negative of a panoramic view, such as is taken by a "Cirkut" camera. At present, views of these negatives are printed by contact exposure, and when an enlargement is required, owing to the extreme length of the picture, it can only be done in sections. The result thereby attained is seldom satisfactory, not only because of the unavoidable line at the junction of each section but because of the difficulty in exactly matching the sections at the junction, both in location and tone.

The invention, which is the subject of this application has been devised to obtain a satisfactory enlargement by moving the negative film across a plate having a cross slit through which the printing light is admitted, the representation of the picture where it passes the slit being enlarged by passing it through a lens on to a printing paper of the required size, which paper travels in the opposite direction at a speed proportioned to the ratio of the required enlargement, the negative film and the printing paper being moved simultaneously by a mechanism provided. The particular means by which this result may be carried into effect is fully set forth in the following specification, reference being made to the drawings by which it is accompanied, in which:

Figure 1 is a vertical longitudinal section on the line 1—1 of Fig. 2, Fig. 2, a horizontal section on the line 2—2 in Fig. 1, and Fig. 3, an enlarged detail of a frictional check for the rollers.

Rotatably mounted at one end of a suitable frame 2 are film rollers 4 and 5, one on each side of a plate 3 having a slit 6 extending across the width of the film. On one of these rollers 4 the film 20 to be

printed is wound and the end of it is carried across the plate 3 and connected to the film receiving roller 5, which has provision for rotating it, a friction device being provided on the roller 4 to impose resistance to its movement sufficient to maintain the film tightly drawn across the plate 3. The frictional check may conveniently take the form of a dished resilient washer 16, as shown in Fig. 3. Secured to and projecting inward from the apertured end plate 3 and in alinement with its slit, a lens is introduced at 7, which lens is adjustable in any approved manner in its distance from the slit 6. Within the other end of the frame 2 printing reels 8 and 9 are mounted to be rotatable one on each side of the middle line. On the reel 8, which is on the opposite side of the middle line to the film reel 4, the printing paper 21 is wound and its end is carried across a plate 10 and attached to the roller 9. These printing rollers 8 and 9 are of a width and diameter corresponding to the desired enlargement and the roller 9 is driven at the same speed of rotation as the negative film receiving roller 5 by a shaft 11 on which worms 12 and 13 are secured, 12 meshing with the teeth of a worm wheel 14 secured to the film receiving roller 5 and 13 meshing with a worm wheel 15 secured on the print receiving reel 9.

To enable the shaft 11 to be rotated at a regular and slow rate of speed by hand and to facilitate variation of that speed to suit different printing papers the shaft 11 may be rotated by a worm gear (similar to that which is used for rotating the reels 5 and 9) from a cross shaft 17 rotatable in bearings in the base frame of the device, and provided with a small crank handle 18.

The device may be arranged to give any desired ratio of enlargement by proportioning the distance from the lens to the printing paper 21 in relation to the distance from the slit to the lens, that it shall be the same ratio that the diameter and width of the rollers 8 and 9 bear to those of the negative film rollers 4 and 5.

The rollers 8 and 9 may be made of smaller size and be driven at an increased speed. But the arrangement here set forth of using a diameter of roller of the required proportion and driving it at the same speed is preferred, as the different thickness of

the printing paper in relation to the thickness of the film is thereby conveniently provided for.

We do not desire to be confined to the exact construction here set forth of arranging the several parts, or for simultaneously operating the film and printing paper reels, as the same may be varied to suit the requirements of construction without departing 10 from the spirit of the invention.

What we therefore claim and desire to be protected in by Letters Patent, is:

1. A device for photographically enlarging a picture from a negative film, said device comprising the combination with a suitable supporting frame, of a plate at one end having a light admitting slit, a lens intermediate of the ends of the frame in axial alinement with the slit, a roller rotatably 15 mounted on one side of the slit plate on which roller the negative film is wound, a film receiving roller rotatably mounted on the other side of the slit to which roller the film is connected across the slit plate from the other roller, a plate at the other end of the frame at the required distance from the lens to give the desired enlargement of the picture, a roller mounted on one 20 side of this plate on which roller a strip of printing paper is wound, a roller rotatably mounted on the other side of this plate to which roller the strip of printing paper is connected across the plate from the other roller the diameter of the print receiving 25 roller being proportioned to that of the film receiving roller in the ratio of the desired enlargement, and means for simultaneously

rotating the two receiving rollers at a uniform speed.

2. A device for photographically enlarging a picture from a negative film, said device comprising the combination with a suitable supporting frame, of a plate having a light admitting slit, a roller having a film wound on it, said roller rotatably mounted on one side of the slit plate, a film receiving roller rotatably mounted on the other side of the slit plate to which roller the end of the film is attached across the plate, a lens the axis of which is in alinement with the slit, a plate normal to the axis of the lens at the required distance from it to give the desired enlargement, a roller on which a strip of photographic printing paper is wound, which roller is rotatably mounted on one side of the plate, a print receiving roller rotatably mounted on the other side of the plate to which roller the printing paper from the other roller is attached across the plate, means preventing free rotation of the roller on which the film is initially coiled, means preventing free rotation of the roller on which the printing paper is initially wound, and means for simultaneously rotating the film receiving reel and the print receiving reel.

In testimony whereof we affix our signatures in presence of two witnesses.

HOMER E. LEASH.
JOHN L. SCHWENK.
